MUSICAL INSTRUMENT

William Frederick Rebsamen, North Little Rock, Ark., assignor of one-half to Bean Music Company, Little Rock, Ark.

Application March 22, 1938, Serial No. 197,501

2 Claims. (Cl. 84—319)

This invention relates to a musical instrument of the banjo type, one of the objects being to provide such an instrument designed primarily for use by players accompanying harmonicas, one of the objects being to provide a simple, inexpensive and attractive instrument of this character the playing of which can be learned quickly.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

In the accompanying drawing the preferred form of the invention has been shown.

In said drawing:

20 Figure 1 is a plan view of the instrument.

Figure 2 is a side elevation thereof.

Figure 3 is a section on line 3—3 of Figure 1, said section being enlarged.

Figure 4 is a section on line 4—4 of Figure 1.

Referring to the figures by character of reference 1 designates a flat board preferably of veneer and which follows the contour of a circle through approximately 270 degrees, the periphery of the board then merging along curved lines into the sides of an elongated neck 2, the head 3 of which is provided with frictionally held keys 4 for engagement with the strings 5 of the instrument. These strings are fastened at their other ends to the board 7 by the usual or any other preferred means, as shown particularly at 6 and also extend over a bridge 7 located adjacent to a central opening 8 in the board.

A circular baking pan or the like indicated at 9 has its open face covered by the board 1, this pan being concentric with the board and secured thereto at its margin in any suitable manner, as by means of a strong adhesive. The pan cooperates with the board to form the body of the instrument. Extending from the pan is a bar 10 which is arranged back and longitudinally of the neck 2 and cooperates therewith to stiffen the same.

Suitably located frets 11, 12, 13 and 14 are provided on the neck 2 and in the instruments thus far produced the fret 11 has been employed for sounding the chord of C-major while the fret 14 has been employed for sounding the octave.

Secured to the neck 2 adjacent to fret 12 is a resilient loop 15 which bridges the strings 5. This loop of spring material carries a contact roller 16 which also extends across but the resilient loop on which it is mounted supports the roller out of

contact with the strings 5. Another resilient loop 17 is secured to the neck 2 and also carries a roller 18 normally spaced from but extending across all of the strings 5. Roller 15 is disposed adjacent to fret 12 while roller 18 is located adjacent to fret 13. These parts are so arranged that when roller 16 is depressed the resilient loop is sprung out of normal position and the roller is brought into contact with the strings 5. Thus the dominate chord can be sounded. However when 10 roller 18 is thrust against the strings in a similar manner, the sub-dominant chord can be sounded.

With this arrangement of frets and with the yieldingly supported normally inactive contact members 16 and 18 located as stated, the instrument can be used effectively for accompanying persons playing harmonicas and the tone produced has been found to blend satisfactorily with that of such instruments.

Although the parts 16 and 18 have been designated as rollers, it is to be understood that they can be of any desired construction and need not necessarily be mounted for rotation on a supporting means. They merely constitute chord bars which can be depressed readily by the player whenever either the dominate or the sub-dominant chord is desired. For the purpose of playing the chord of C-major or its octave, the player merely depresses the strings so as to engage the respective frets 11 and 14.

What is claimed is:

1. A musical instrument including a pan, an apertured board secured thereto and having a neck, strings extending along the neck and across the board, frets for engagement by but normally out of contact with the strings, spring loops anchored at their ends in the neck and extending across and normally out of contact with the strings, said strings being extended through the loops and between said loops and the neck, each loop constituting a chord bar positioned adjacent a predetermined fret and movable under pressure against the strings and out of normal position.

2. A musical instrument including a pan, an apertured board secured thereto and having a neck, strings extending along the neck and across the board, frets for engagement by but normally out of contact with the strings, spring loops anchored at their ends in the neck and extending across and normally out of contact with the strings, said strings being extended through the loops and between said loops and the neck, and a roller yieldingly supported by the loops and across but out of contact with the strings, said roller being movable against the strings when 55 subjected to sufficient pressure to flex the loops.

WILLIAM FREDERICK REBSAMEN.
